UNITED STATES PATENT OFFICE.

RICHARD H. TRESTED, OF JERSEY CITY, NEW JERSEY.

METHOD OF MAKING HATS.

SPECIFICATION forming part of Letters Patent No. 367,253, dated July 26, 1887.

Application filed October 21, 1886. Serial No. 216,852. (No model.)

To all whom it may concern:

Be it known that I, RICHARD H. TRESTED, a citizen of the United States, residing at Jersey City, in the county of Hudson and State 5 of New Jersey, have invented new and useful Improvements in Methods of Making Hats, of which the following is a specification.

My invention relates to an improved method or process of making hats in imitation of straw 10 or other braid, for the use of ladies, gentlemen, and children.

To such end the invention consists in the novel method hereinafter described, and definitely set forth in the claims.

15 In the accompanying drawings, Figure 1 represents a perspective view of a hat embodying my invention. Fig. 2 is a section of a portion thereof on a larger scale than the previous figure.

20 Similar letters indicate corresponding parts.

In the drawings, the letter A designates the molded support, and B is the flexible ornamental shell.

25 In carrying out my invention I take a piece of woven fabric made from cotton or wool or any other substance suitable for the purpose—such as leather or paper—and this fabric I treat with a solution of shellac or any other suitable material to impart to the fabric the 30 required stiffness. Of this stiffened fabric I cut a piece the size required for a hat and press the same into the desired shape by means of suitable heated dies, in the same manner as usually done by the manufacturers of hat and 35 bonnet frames. The article thus produced forms what I term the "molded" support of my hat.

For the purpose of producing the flexible ornamental shell of my hat I proceed as follows: I take a mold, the inner surface of which 40 is formed with suitable designs, lines, characters, or marks to correspond to the ornaments to be produced on the outer surface of the shell in imitation of straw or other braids, and 45 into this mold I pour the molding-sirup or plastic composition while hot, allowing only that portion of the sirup or plastic composition which sticks to the inner surface of the mold to remain until it has cooled off, the re- 50 mainder of the sirup being poured out of the two or more thicknesses of muslin, or other

mold after having remained therein for about five to ten minutes.

The molding-sirup or plastic composition which can be used for my purpose with advantage is prepared as follows: I take eight pounds of glue and allow it to soak in water for five hours, then I pour off the water, then take the glue and melt it in a suitable kettle. If too thick, I add a little water. To the 55 melted glue I add two pounds of shellac and one and three-quarter pound of paraffine and heat until the entire mass has melted, then I add one gallon of molasses and half a pint of glycerine; then boil all for about one hour; 60 and if it is desired to give to the mass a more solid body I use a small quantity of pigment, such as zinc-white, chrome-yellow, or amber.

In order to impart to the mass a black color, I prepare a black paste by boiling three-quarters of a gallon of old linseed-oil to the consistency of a thick varnish, then adding to the same while hot three pounds powdered resin and next three-quarter pounds dry brown-soap shavings, then mixing with the mass one and a 75 quarter ounce paris blue and two and a-half pounds lampblack. After standing for a week this mass must be ground, when it is ready to be mixed with the molding-sirup above described in such proportion as may be required 80 to produce a jet-black.

I do not wish to confine myself to the molding-sirup as above described, since other compositions might be used, but by means of the molding sirup above described I have obtained 85 satisfactory results.

That portion of the molding sirup which adheres to the inner surface of the mold, as above stated, after having cooled, can be readily removed, and it forms a flexible shell, the external surface of which is ornamented in imitation of straw or other braid. This flexible shell of plastic composition is drawn over the stiff molded support and made to stick thereon by any suitable adhesive, such as rubber cement. By these means a hat is obtained which 90 is very light, not liable to crack or break, of superior durability, and to become hard. Furthermore, my hat can be furnished in any desired color, and its cost is very low.

100 I am aware that a hat or bonnet has heretofore been made the body of which is made of

suitable fabric, shaped or formed with a series of raised or embossed stripes, in imitation of straw or other braid, by means of suitable dies. I am also aware that a hat has been heretofore made by me of a stiff support and a flexible sheet-metal facing having an embossed external surface. Such features, however, do not constitute my present invention, and are not herein claimed by me.

10. What I claim as new, and desire to secure by Letters Patent, is—

1. The method herein described of making hats, which consists in forming a flexible shell from a plastic composition in a mold, removing said shell from the mold and drawing it over a stiff support having the form of the hat desired, and cementing the internal surface of the plastic composition shell to the external surface of the stiff support, substantially as set forth.

2. The method herein described of making hats, which consists in molding a flexible shell of plastic composition with an external sur-

face, in imitation of straw or other braid, and then drawing such flexible shell over a stiff support having the form of the hat desired, and uniting the internal surface of the shell to the external surface of the support, substantially as set forth.

3. The method herein described of making hats, which consists in molding a stiff support into the form of hat desired, pouring a heated composition into a mold furnished with the ornamentation to be imparted to the exterior of the hat, cooling the composition, and forming a thin flexible shell, drawing such shell over the molded support, and cementing the shell and support together, substantially as set forth.

In testimony whereof I have hereunto set my hand and seal in the presence of two subscribing witnesses.

RICHARD H. TRESTED. [L. S.]
